DESIGN FOR A DRESSING TABLE

James J. O'Neill, Oakland, Calif.

Application February 4, 1936, Serial No. 60,967

Term of patent 14 years

To all whom it may concern:

Be it known that I, James J. O'Neill, a citizen of the United States, residing at 385 Jayne Avenue, Oakland, California, have invented a new, original, and ornamental Design for a Dressing Table, of which the following is a specification, reference being had to the accompanying drawing, forming part thereof.

Figure 1 is a top plan view of the dressing table showing my design.

Figure 2 is a perspective view.

Figure 3 is a side elevational view.

The area of the glass table-top which is stippled is opaque, the unstippled area being transparent.

I claim:

The ornamental design for a dressing table substantially as shown and described.

JAMES J. O'NEILL.
